DESIGN FOR AN ELECTRIC SHOE SHINER

Ruth G. Getgey, Cincinnati, Ohio, assignor to
Empire Products, Inc., Cincinnati, Ohio, a cor-
poration of Ohio

Application July 28, 1943, Serial No. 110,779

Term of patent 14 years

To all whom it may concern:

Be it known that I, Ruth G. Getgey, a citizen
of the United States, residing at Cincinnati, in
the county of Hamilton and State of Ohio, have
invented a new, original, and ornamental Design
for an Electric Shoe Shiner, of which the follow-
ing is a specification, reference being had to
the accompanying drawing, forming a part
thereof.

Fig. 1 is a perspective view of an electric shoe
shiner showing my new design.

Figure 2 is a side elevational view thereof.
Figure 3 is a top plan view thereof.

I claim:

The ornamental design for an electric shoe
shiner, substantially as shown.

RUTH G. GETGEY.
